UNITED STATES PATENT OFFICE.

CHAPMAN J. ROOT, OF TERRE HAUTE, INDIANA.

DESIGN FOR A BOTTLE.

Application filed December 12, 1921. Serial No. 521,940. Term of patent 14 years.

To all whom it may concern:

Be it known that I, CHAPMAN J. Root, a citizen of the United States, residing at Terre Haute, in the county of Vigo and State of Indiana, have invented a new, original, and ornamental Design for Bottles, of which the following is a specification, reference being had to the accompanying drawings, forming part thereof.

The figure is a side elevation of a bottle showing my new design.

I claim as my invention:

The ornamental design for a bottle as shown.

In witness whereof I, CHAPMAN J. Root, have hereunto set my hand at Indianapolis, Indiana, this December, A. D. one thousand nine hundred and twenty-one.

CHAPMAN J. ROOT.
